CRYSTAL INSERTER

Edmond Junod, Lausanne, Switzerland

Application March 28, 1935, Serial No. 13,553
In Switzerland April 11, 1934

5 Claims. (Cl. 29—84)

This invention relates to crystal inserters, particularly to devices for inserting non-breakable and non-circular watch crystals and belonging to the type of those comprising two tools which are 5 movable one relative to the other and of which one serves as support for the bezel into which the crystal is inserted, while the other serves to push the edge of the crystal into the crystal receiving groove of the bezel.

10 The primary object of the invention is to provide a crystal inserter of the above type which does not exert any excessive stress on watch bezels, even on very small and weak bezels which do not permit much opening, and which may 15 even be used with bezels of jewelry.

A further object is the provision of a crystal inserter which enables the inserting operation to be done rapidly by adapting the device to operate on all possible types and shapes of bezels, and 20 also permits the inserting operation to be done under high pressure which it is impossible to obtain by hand insertion, and which is equivalent to the pressure applied with the inserting devices used heretofore for inserting non-breakable circular crystals in circular bezels.

25 Other objects will appear from the following description of a preferred embodiment of the invention, reference being had to the accompanying drawing in which,

30 Figure 1 is a side elevation of a crystal inserter according to the invention.

Figure 2 is a plan view of the lower portion of the device.

Figure 3 is a section along the line 3—3 of 35 Figure 2.

Figures 4 and 5 are fragmentary views of the cooperating tools in two different positions of operation.

The represented apparatus comprises a frame 40 mounted on a base plate 2 provided with holes 3 permitting the apparatus to be secured on a stand or bench.

A plate 30 is mounted on the base 2 and carries 45 a horizontal disk or turntable 4 which can turn about a trunnion screw 5. The disk 4 carries two supporting tools 6 and 7 extending along a diameter of the disk. This disk is provided with two diametrically opposed recesses 8 and 9, the diameter on which the same are placed extending at 50 right angles to the diameter on which are placed the tools 6 and 7. The two recesses serve to lock the disk 4 in two different positions at an angle of 180° one from the other, by means of a bolt 55 10 pivoted on a pin 37 and subjected to the action

of a spring 38 tending to maintain the bolt engaged in the slot of the disk.

A projecting portion 31 of the plate 30 engages a slot in the base 2. The screw 5 screws into a clamping plate 32 which is slightly larger than 5 the slot and pulls the plate 32 against the plate 30 which is thus fixed to the base 2. The clamping plate 32 carries a pin 39 which traverses an oblong hole 40 provided in a lever 33 pivoted at 34 and operable by a nut 36 screwing on a stud 10 35 of the lever 33 which penetrates through a slot 45 of the base member 2. This mechanism permits adjustment of the disk 4 with the tools 6 and 7 relative to the other parts of the apparatus. 15

The frame 1 forms an arm 11 the free end of which is provided with two vertical bores of rectangular cross section in which are slidably mounted two bars 12 and 13 of corresponding cross section. The lower end of each bar forms 20 a socket 14 of larger cross section than the bars so as to limit the upwards movement of the bars. In each socket 14 is mounted a block 15 and 16, respectively, of a resistant but somewhat resilient material, as for example fibre or ebonite. 25 The two bars 12 and 13 carry each an upwardly extending rod 17 and 18 serving to hold a spring 19 inserted between a washer 20 carried on the arm 11 and a nut 21 screwed on the top of each rod 17 and 18 and operable to adjust the pressure 30 of the spring 19 which maintains the bars 12 and 13 in their raised position.

The bar 12 carries a pin 22 extending laterally through a slot 23 provided in the arm 11 and engaging a slot 25 provided in a lever 24 which 35 is pivoted on the arm 11. When acting on the lever 24 in direction of the arrow f, the bar 12 can be lowered against the action of the spring 19 which returns the bar to its raised position as soon as the lever 24 is released. 40

A similar operating mechanism, comprising a lever 26, is provided on the other side of the arm 11 for lowering the bar 13.

As it can be seen in Figure 1, the bar 12 is 45 positioned so that its end 15 can coact with the supporting tool 6 when the disk 4 is in the represented position. When the disk is turned through 180° the supporting tool 7 arrives in a position in which it can coact with the end 16 of the bar 13.

The described apparatus operates in the following manner: First the disk 4 is brought to the position shown in Figure 1. After the crystal 43 has been placed over the bezel 42 which, as shown in Fig. 4, is hingedly connected at 44 to the back 41 of a watch case, the bezel is placed 55

over the end face 28 of the supporting tool 6. Then the lever 24 is actuated to lower the bar 12 and the block 15 presses on the edge of the crystal in order to introduce it into the groove 27 of the bezel. This bezel can be moved to various positions on the support 6 and the crystal will be inserted in its groove along the entire contour of the bezel except on that side on which is disposed the hinge 44 of the watch case. Then the disk 4 is turned through 180° and the part of the bezel adjacent the hinge 44 is placed on the support 7 (Fig. 5). Then the lever 26 is actuated to press the block 16 on that edge of the crystal which is situated adjacent the hinge 44 and to insert also this edge into the groove of the bezel.

In order to avoid any damage of the bezel, the faces of the tools 6 and 7 are coated with lead, tin, leather or other materials which, though being quite resistant, are slightly yielding. Thus the edge of the bezel makes a slight impression on the face of the supporting tool whereby guiding of the bezel by hand is facilitated.

The working faces 28 and 29 are relatively large compared with that of the supporting tools of known inserting devices. This face of the tools 6 and 7 is large enough in radial direction relative to the bezel placed on it, that the bezel bears on this face simultaneously with the internal face of its peripheral wall and with the internal edge situated beneath the crystal receiving groove, as appears from Figures 4 and 5, while the supporting face is also large in longitudinal direction relative to the bezel so that an important fraction of the length of the bezel rim bears on this face. The faces 27 and 28 are inclined in opposed directions relative to the horizontal when they are in working position. The purpose of this inclination is that the pressure exerted on the crystal is slightly inwardly directed relative to the bezel.

In practice it will not be necessary at all times to use the inserting tool 15 together with the supporting tool 6 and the tool 16 with the support 7; there may be cases in which it will be advantageous to have the tool 15 coact with the support 7, and the tool 16 coact with the support 6.

The levers 24 and 26 could be pivoted at a point of the frame situated so that in order to lower the slide tools 15 and 16, these levers would have to be turned in a direction opposite to that indicated by the arrow *f*. These slide tools could also be arranged for being actuated by means of foot pedals instead of hand levers.

It is also possible, instead of mounting the tools on the fixed frame 1, to mount the turntable 4 with the supporting tools on one jaw of a pair of pliers and the inserting tools 15 and 16 on the other jaw.

The described apparatus is particularly advantageous for inserting crystal into bezels which are decorated with precious stones and where the supporting tool may not bear on the bezel at any other place than on the internal rim which is provided with the crystal receiving groove.

I claim:—

1. A crystal inserter comprising a frame, a bezel supporting tool carried by the frame, said tool having a bearing face adapted to support the bezel over the entire width of the bezel and over an important fraction of the length of the band, a movable inserting tool adapted to exert pressure on the edge of the crystal for inserting the same in the crystal receiving groove of the bezel, said inserting tool being slidably mounted on said frame, and an operating lever for moving said inserting tool.

2. A crystal inserter comprising a frame, a crystal inserting tool slidably mounted on the frame, a turntable pivoted on the frame, two bezel supporting tools mounted on the turntable whereby one or the other of the supporting tools may be brought into working position for coacting with the inserting tool, and means for moving the inserting tool towards and away from the supporting tool in working position, whereby the inserting tool may be moved to engage an edge of the partially fitted crystal and insert it in the crystal receiving groove in the bezel placed on the supporting tool.

3. A crystal inserter comprising a frame, a crystal inserting tool slidably carried by the frame, a turntable slidably and pivotally mounted on the frame, two bezel supporting tools carried by the turntable whereby one or the other of the supporting tools may be brought into working position for coacting with the inserting tool, means for locking the turntable against pivotal movement when one of the supporting tools is in working position, means for locking the work table against sliding movement, and means for moving the inserting tool towards and away from the supporting tool in working position.

4. A crystal inserter comprising an inserting tool and a bezel supporting tool movable relative to each other, the bezel supporting tool being provided with a bearing surface adapted to engage the bezel, and the inserting tool having a crystal engaging end positioned relative to the supporting tool in such relation that upon a movement towards each other of the two tools in the absence of a bezel and crystal, the crystal engaging end abuts against the bearing surface of the bezel supporting tool.

5. A crystal inserter comprising a frame, a bezel supporting tool carried by the frame, said tool having a bearing surface adapted to support the bezel over a substantial area thereof, a crystal inserting tool adapted to exert pressure on the edge of the crystal for inserting the same in the crystal receiving groove of the bezel, said inserting tool being slidably mounted on said frame to move towards the bezel supporting tool in such direction that in absence of a bezel and crystal the end of the inserting tool abuts against the bearing surface of the supporting tool, and actuating means for moving said inserting tool.
